UNITED STATES PATENT OFFICE.

WILLIAM B. HALL, OF CHICAGO, ILLINOIS, ASSIGNOR TO UNION RAILWAY EQUIPMENT COMPANY, OF CHICAGO, ILLINOIS, A CORPORATION OF ILLINOIS.

SUPPORTING MEANS FOR DROP-BRAKE SHAFTS.

Application filed June 1, 1925. Serial No. 34,105.

My invention relates to a drop brake mechanism and more particularly to means for supporting the drop brake shaft in raised position.

- 5 It is a purpose of my invention to provide means for holding a vertically movable brake shaft in raised position comprising a member mounted on the brake shaft that engages with a shoulder on a member embracing the same so as to hold the same against downward movement and to provide means for disengaging said member from said shoulder to permit downward movement of said brake shaft when desired.
- 10 15 It is a further purpose of the invention to provide means of the above mentioned character comprising a latching member pivotally mounted in a pocket or recess in the brake shaft and having a normal tendency to project laterally therefrom so as to engage with a shoulder provided on a sleeve surrounding said brake shaft and to provide means for disengaging said latch from said shoulder comprising a pivotally mounted member engaging said latch so as to force or crowd the same off said shoulder when it is desired to release the brake shaft to permit dropping of the same. The latch is 20 25 30 preferably provided with an inclined face with which the releasing member is adapted to engage to move the same into the pocket by a wedging action.

The latch may be movable into position to engage the shoulder either by the action of gravity or by means of a spring or other resilient means. The spring member may itself serve as a latch or may be used merely for moving the pivoted latch into locking position.

- 35 40 45 50 Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

- 55 Fig. 1 is a view partly in elevation and partly in vertical section of a portion of a railway car and a portion of my improved brake mechanism showing the drop brake

shaft and the means for supporting the same in raised position;

Fig. 2 is an enlarged view partly in section and partly in elevation of a portion of the brake shaft and the sleeve surrounding the same showing my improved holding means therefor in position for holding the brake shaft in elevated position;

Fig. 3 is a similar view showing the holding member or latch in releasing position;

Fig. 4 is a front elevation of the parts shown in Fig. 2;

Fig. 5 is a section taken substantially on the line 5—5 of Fig. 2;

Fig. 6 is a section taken substantially on the line 6—6 of Fig. 2.

Fig. 7 is a view similar to Fig. 2 of a modified form of my invention; and

Fig. 8 is a view similar to Fig. 3 of a further modification.

Referring in detail to the drawings, in Fig. 1 is shown a channel member 10 and a plate 11 forming the end sill of a car having the floor 12. Mounted on the channel member 10 is a bracket member 13 having a laterally extending portion 14 which is provided with an opening 15 through which the sleeve 16 extends. Said channel member 10 is also provided with a bracket member 17 which is provided with a detachable cap portion 18, 80 85 90 said bracket member 17 being separate from and spaced from the bracket member 13. The vertically movable brake shaft 19 extends through the bearing member formed by the members 17 and 18 and through the sleeve 16 and is vertically slidably therein. Said brake shaft 19 is provided with the usual hand wheel 20 and the ratchet 21 cooperating with a pawl as is customary.

It will be seen from Fig. 6 that the shaft 95 19 is substantially square in cross section and is bifurcated at the lower end thereof so as to provide a central slot or opening 22. The bifurcated end of the member 19 is provided with pivot holes for the pivot pin 23 100 which has mounted thereon the latch member 24, said latch member being loosely pivoted on the pivot pin 23 due to the fact that the pivot opening 25 is larger than the pivot pin 23. This permits a certain amount 105 of play of the latch member 24 on the pivot pin.

Referring to Figs. 2 and 3, it will be seen that the latch member 24 is provided with a projecting finger 26 on one face 110

thereof which is slightly inclined to the adjacent face 27 of the member 24 and from which the inclined rib 28 extends merging with the member 24 adjacent the upper end thereof to thus provide an inclined surface extending from the forward edge 29 of the locking finger 26 toward the upper end of the latch 24.

The sleeve-like member 16 surrounds the shaft 19 and has the pinion 30 formed thereon, said pinion meshing with a gear 31, both said pinion and gear being mounted within a housing 32 secured to the bracket 13 in any suitable manner. The lower end 15 of the sleeve 16 is provided with a projecting hub portion 33 which is rotatable in a bearing 34 provided on the housing 32. Said member 16 is further provided with pairs of oppositely arranged grooves 35 20 within which the ribs 36 on the member 19 lie whereby the movement of the shaft 19 is guided and is also limited as the ribs obviously cannot travel further than a certain distance in the grooves 35 due to the 25 provision of the stop lugs or projections 37 therein.

The sleeve 16 is further provided with a pair of laterally projecting ears 38 which are provided with the inclined internal slots 39 or grooves 39 terminating in the curved ends 40. A latch releasing member 41 is mounted in the housing 16, being inserted from the interior thereof by passing the laterally projecting pivot members 42 provided thereon down the inclined grooves 39 until the same rest adjacent the rounded ends 40 thereof. A lateral slot or opening 43 is provided in the member 16 to accommodate the releasing member 41 and said 40 releasing member is provided with a forwardly projecting finger portion 44 and an outwardly projecting handle portion 45 which may be provided with a central opening 46 if desired. The finger 44 is provided 45 with a flat forward face 47 and a slightly inclined side face 48 connected by the curved portion 49.

Referring now to Fig. 2, it will be seen that when the shaft is in raised position, the finger 26 will engage with the inclined shoulder 50 provided on the sleeve 16 at the opening 43, said shoulder or face 50 forming the bottom of said opening. The engagement of the locking finger 26 with said shoulder 50 is due to the fact that the latch 24 tends to assume the position shown in Fig. 2 due to the action of gravity, the weight of the member 24 being so distributed relative to the pivot pin 23 that the latch has a tendency to protrude slightly from the pocket or opening 22 in the member 19. Accordingly, when the shaft 19 is raised so that the finger 26 passes the shoulder 50, upon release of the shaft 19 by the person operating the hand wheel 20, the finger 26

will automatically move into engagement with the shoulder 50 to prevent downward movement of the shaft 19 until released. In order to release the latch from the shoulder 50, the locking member 41 is rotated 70 in a counter-clockwise direction from the position shown in Fig. 2 toward the position shown in Fig. 3. The rounded edge 49 engaging with the inclined edge 28 on the member 24 tends to wedge the same in 75 a clockwise direction around the pivot 23.

In order to provide ease of operation of the releasing means, it is desirable to slightly lift the shaft 19 when operating the releasing member 41. When the weight of 80 the parts are on the pivot pin 23, the tendency will be for the pivot pin to lie at the bottom of the opening 25 as shown in Fig. 2, while if the shaft is lifted, the pin 23 will move to the top of the opening 85 28 as shown in Fig. 3 preventing upward movement of the member 24 on the pivot pin 23 when the projecting finger portion 44 of the releasing member 41 engages therewith. The counter-clockwise movement of 90 the member 41 is continued until the latch is moved entirely within the pocket in the member 19 as shown in Fig. 3, the engaging portion of the unlocking member 41 at this time being the flat forward face 47 thereof 95 which by this time engages with the slightly inclined forward edge 29 of the member 26. The shaft 19 then drops and the member 41 is released assuming the position shown in 100 Fig. 2 due to the action of gravity, the handle portion 46 thereof being heavier than the portion 44 to thus cause the automatic movement of said member to the position shown in Fig. 2.

In Fig. 7 a different form of locking 105 means is shown for holding the shaft 19 in raised position. The sleeve 16 is provided as in the form previously described and is provided with an opening or slot 60 providing a shoulder 61 at the bottom thereof 110 with which the latch 62 is adapted to engage. Said latch is made of spring metal and the lower end portion thereof normally inclines outwardly of the shaft 19 as shown in Fig. 7, the upper portion thereof lying in the recess 63 in said shaft 19 and being secured thereto by means of the fastening member 64. The shaft 19 is provided furthermore with a recess 65 which is deeper 115 than the recess 63 so as to accommodate the spring 62 when the same is moved to the left in Fig. 7 out of engagement with the shoulder 61. The spring latch 62 is moved into unlocking or releasing position by 120 means of the releasing member 41 which is substantially the same as that shown in Figs. 1 to 6 inclusive, the same being pivoted in the same manner as previously described in connection with Figs. 1 to 6 by means of the 125 pivot members 42 engaging with the pivot 130

ears 38. The forwardly projecting finger portion 44 of the releasing member 41 engages with the spring latch 62 in substantially the same manner as the releasing member engages with the latch in the other figures, crowding the same to the left in Fig. 7 out of engagement with the shoulder 61.

Instead of providing a spring that directly engages with the shoulder, the spring means may be used for urging the latch into such a position that the same will engage with the shoulder on the sleeve. Such an arrangement is shown in Fig. 8 in which the shaft 19 is provided with a slot 66 within which is pivoted the latch 67, said latch being pivoted on the pivot pin 68 and having a pivot opening 69 larger than the pin 68 so as to loosely pivot the member 67 on the pin 68 in the same manner as the member 24 is pivoted on the pin 23 in Figs. 1 to 6 inclusive and for the same purpose. Said latch is provided with a shoulder 70 that is adapted to engage with the shoulder 71 at the bottom of the slot 72 provided in the sleeve 16. Said latch is further provided with a downwardly extending projection 73 that is adapted to engage with the inner wall 74 of the sleeve 16 to limit the movement of the latch 67 outwardly into the slot 72. Said latch is further provided with a spring member 75 that is secured in any suitable manner as by means of the upset lugs 76 to the latch 67, said spring 75 engaging with the inner wall 77 of the slot 66 and normally tending to move the member 67 counter-clockwise around the pin 68.

In Fig. 8 the spring is shown as being compressed against the wall 77 due to the fact that the forwardly projecting rounded end portion 44' of the releasing member 41 is in engagement therewith, the spring being then under tension. In the form shown in Fig. 8, the operation is the same as in the form shown in Figs. 1 to 6 inclusive except that spring means is provided instead of gravity means for holding the latch in locking position. To release the same the shaft 19 is slightly raised and the releasing member 45 is swung about its pivot to engage with the pivoted latch 67 to crowd the same off the shoulder 71. In Fig. 7 due to the resilient nature of the member 62, it is not necessary to raise the same to disengage the latch from the shoulder. In order to protect the end of the spring 62 in Fig. 7, the shaft 19 is provided with a projection 78 extending below the bottom of the spring 67 to thus house the same within the confines of the shaft 19 when the same is out of engagement with the shoulder 61.

Having thus described my invention, what I desire to claim and secure by United States Letters Patent is:

1. In a device of the character described, a brake shaft, means for mounting said

brake shaft on a car for vertical movement, a sleeve surrounding said brake shaft and having an internal inclined shoulder intermediate its ends, and means for supporting said brake shaft in raised position comprising a member on said brake shaft engaging said shoulder on said sleeve when said brake shaft is raised.

2. In a device of the character described, a brake shaft, means for mounting said brake shaft on a car for vertical movement, a sleeve surrounding said brake shaft, means for supporting said brake shaft in raised position comprising a member on said brake shaft engaging a shoulder on said sleeve when said brake shaft is raised, and means for disengaging said member from said shoulder to permit lowering of said brake shaft.

3. In a device of the character described, a brake shaft, means for mounting said brake shaft on a car for vertical movement, a sleeve surrounding said brake shaft and means for supporting said brake shaft in raised position comprising a member having its upper end pivotally mounted on said brake shaft engaging an internal shoulder on said sleeve when said brake shaft is raised.

4. In a device of the character described, a brake shaft, means for mounting said brake shaft on a car for vertical movement, a sleeve surrounding said brake shaft, means for supporting said brake shaft in raised position comprising a member pivotally mounted on said brake shaft engaging a shoulder on said sleeve when said brake shaft is raised and a releasing member pivotally mounted on said sleeve and engaging said member on said brake shaft to move the same off said shoulder.

5. In a device of the character described, a brake shaft, means for mounting said brake shaft on a car for vertical movement, a sleeve surrounding said brake shaft, a latch mounted on said brake shaft and having a normal tendency to extend outwardly beyond said shaft and engage a shoulder on said sleeve to hold said shaft in raised position and means for crowding said latch off said shoulder.

6. In a device of the character described, a brake shaft, means for mounting said brake shaft on a car for vertical movement, a sleeve surrounding said brake shaft, a latch mounted on said brake shaft and having a normal tendency to extend outwardly beyond said shaft and engage a shoulder on said sleeve to hold said shaft in raised position, said latch having an inclined face, and a releasing member mounted on said sleeve and engaging said inclined face to move said latch off said shoulder.

7. In a device of the character described, a brake shaft, means for mounting said

- brake shaft on a car for vertical movement, a sleeve surrounding said brake shaft, said shaft having a pocket therein, a latch pivotally mounted in said pocket and tending to project therefrom, said latch engaging a shoulder on said sleeve to hold said shaft in raised position and means on said sleeve engaging said latch to force the same into said pocket to permit said shaft to drop.
8. In a device of the character described, a brake shaft, means for mounting said brake shaft on a car for vertical movement, a sleeve surrounding said brake shaft, means for supporting said brake shaft in raised position comprising a member loosely pivoted on said brake shaft engaging a shoulder on said sleeve when said brake shaft is raised and a releasing member pivotally mounted on said sleeve and engaging said member on said brake shaft to move the same off said shoulder with a wedging action.

In witness whereof, I hereunto subscribe my name this 29th day of April, 1925.

WILLIAM B. HALL.
